UNITED STATES PATENT OFFICE.

ROY MURRAY, OF AGENDA, KANSAS.

TIME-CONTROLLED SWITCH.

1,161,068.

Specification of Letters Patent. Patented Nov. 23, 1915.

Application filed November 13, 1914. Serial No. 871,931.

To all whom it may concern:

Be it known that I, ROY MURRAY, a citizen of the United States, residing at Agenda, in the county of Republic and State of Kansas, have invented certain new and useful Improvements in Time-Controlled Switches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to time controlled switches, and has for its principal object to provide mechanism for automatically moving a switch to closed and open positions at determined intervals by means of clock mechanism, together with setting devices for determining the hour of closing and opening the switch. In accomplishing this object I have provided the improved details of structure hereinafter described and illustrated in the accompanying drawings, wherein:—

Figure I is a rear view of the apparatus including the switch, clock-mechanism and setting dials. Fig. II is a front view on the section II—II, Fig. VII, with a part of the front clock frame plate broken away to illustrate the actuating parts. Fig. III is a front view of the clock, with a part of the dial broken away. Fig. IV is an elevation on the line IV—IV, Fig. VII, showing the setting dial gears and the gearing for actuating the switch shaft. Fig. V is an elevation on the line V—V, Fig. VII, showing the gearing for actuating the switch shaft and the secondary switch escapement latch and its controlling parts. Fig. VI is an elevation on the line VI—VI, Fig. VII, showing the primary switch escapement latch. Fig. VII is a plan view of the mechanism. Fig. VIII is a detail view of the switch shaft and its escapement. Fig. IX is a section on the line IX—IX, Fig. V, showing the setting parts and escapement cams.

Referring more in detail to the parts: 1 designates an electrical switch of any ordinary construction, here shown to be of the ordinary knife blade type, comprising the posts 2 and contact plates 3, which are adapted, when in one position, to contact the posts 2. Connected with the plates 3 is a rod 4 which is mounted on the crank 5 of a shaft 6, which is journaled in the frame

plates 7—8 of an ordinary clock and adapted for actuation through gearing 9, of ordinary construction, from a spring motor 10, having the usual pawl and ratchet winding device 11. The clock mechanism comprises a minute arbor 14 which is driven by suitable gearing 15 from a spring motor 16 like the arbor of any ordinary clock.

Meshing with one of the wheels 17 of the gearing 15 that drives the minute arbor 14 is a gear wheel 18 which is fixed on a shaft 19 that is revolvably mounted in the frame members 7—8 and extended thereacross; the wheel 18 being so geared as to make one revolution with every twenty-four revolutions of the minute hand.

Frictionally mounted on the shaft 19 are spaced gear wheels 20—21; the former of which meshes with a pinion 23 that is fixed on a sleeve 24 that is revolvably mounted on a shaft 25 that is journaled in the forward clock frame plate 8 and extended loosely through the rear plate 7 so that the sleeve 24 may turn freely in the plate 7 and on the shaft 25. The sleeve 24 carries a clock dial 27, and fixed on the shaft 25 in front of the dial, is a pointer 28 for use in determining by its relation to the dial, the hour at which the switch may be set, as will presently be more fully described.

Meshing with the gear wheel 21 on the shaft 19 is a pinion 30 which is fixed on the sleeve 31 of the second setting disk 32, which is revolvably mounted on the shaft 33 which is journaled in the frame plate 8 and in the sleeve, so that the sleeve with the dial 32 and gear wheel 30 may revolve on the shaft to set the disk relative to the pointer 34. Fixed on the shafts 25 and 33 are pinions 35, both of which mesh with a single gear wheel 36 on the shaft 19, so that when the shaft 19 is revolved by the gearing connecting the same with the minute shaft of the clock, both of the shafts 25 and 33 may be revolved simultaneously and at the same speed. Fixed to the gear wheels 20 and 21 are cams 38 and 39, having step-offs 40 and 41 respectively.

Pivottally mounted on a shaft 42 which is fixed to and extends between the clock frame plates 7—8 is the secondary escapement latch 43, having an arm 44 yieldingly held against the cam 39 by a spring 45, and having yoke arms 46 and 47 projected along opposite sides of the shaft 6; the arm 47 having a hook 49 on its inner face adapted

for holding a pin 50 that projects laterally from a disk 51 that is fixed on the switch shaft 6; the arm 46 being adapted for projection into the path of the pin to stop the same. Also pivotally mounted on the shaft 42 is the primary escapement latch 52, having an arm 53 held in yielding engagement with the cam 38 by a spring 54 and an opposite arm 57 provided with a hook 58 that is adapted for holding a pin 59 that projects from the opposite face of the disk 51, and is adapted for movement by its cam into position for stopping the switch shaft when the shaft has been released by the movement of the stop arm 46 of the secondary escapement latch out of the path of the pin 50.

In order to impart a better understanding of the construction and operation of the mechanism I will describe its operation.

Presuming the parts to be constructed and assembled as described, with both of the spring motors tensioned and the clock in operation, should it be desired that the switch be closed at a predetermined time, say at eight o'clock in the evening, in order to turn current into the electric lights in a display window of a store, and that the switch be opened at a later hour, say at twelve o'clock p. m., in order to extinguish the lights and thereby save current without requiring the services of an attendant, the setting dial on the sleeve 24 is turned until the hour numeral 8 thereon underlies the pointer 28. While the dial is being turned, the sleeve 24 revolves on the shaft 25 which is held stationary by its gear connection with the shaft 19 that is in gear with the minute shaft of the clock, but the movement of the dial turns the gear wheel 20 so that it turns on its frictional mounting on the shaft 19 to bring the cam 38 into proper relation with the primary escapement latch 52, so that when the hour hand of the clock has reached the hour indicated on the setting dial 27, the step-off of the cam will pass beneath the arm 53 of the latch and the set arm be drawn downwardly by the tension of its spring to lift the hook end of the latch out of engagement with the pin on the holding disk on the switch shaft to release the latter to the actuation of its spring motor. When the switch shaft is released as described, it is revolved by the motor and the crank 5 actuated to throw the switch over into closed relation with the contact posts to close a circuit. The switch shaft 6 continues to revolve when released as described, and when it has turned a half revolution the pin 50 on the opposite side of the disk is caught by the hook 49 on the arm 43 of the secondary escapement latch and the disk held against the tension of the spring motor so that revolution of shaft 6 is stopped and the switch held in closed position. With the parts in this relation the shaft 19 continues to re-

volve through its connection with the minute arbor of the clock, and as the hour indicated on the second setting dial 32 approaches, the step-off of the cam 39 approaches, the arm 43 of the secondary escapement latch, and, when the hour is reached, the arm 43 is drawn down over the cam step-off to lift the hook end 49 of said latch out of contact with the pin 50, and thereby permit a second actuation of the crank shaft that throws the crank back to its original position and thereby retracts the switch rod and pulls the switch out of engagement with the contact members to open the switch to cut off the current, thereby extinguishing the lights when the apparatus is utilized with the lighting system heretofore mentioned. If the mechanism is adapted for use only for the purpose described, that is, to turn lights on at a predetermined hour and turn them off at a later hour, the clock mechanism may be undisturbed and continue to operate throughout the day.

After the mechanism has operated as described, as the hour approaches for actuating the primary latch, the rise of the cam 39, in advance of the step-off, lifts the arm 43, so that the stop arm 46 is moved out of contact with the pin 50 to enable the pin to pass, but synchronously with the movement of the stop arm 46, the clutch arm 58 of the secondary latch is moved into position for engagement by the pin 59, so that when the disk 51 is released by the secondary latch, it is engaged by the primary latch to prevent its actuation by the spring motor. When the hour is reached for closing the switch, the operation heretofore described is repeated and the closing of the switch is effected in a like manner at the later hour; the operation being repeated as long as the clock continues to run and the setting dials remain in their original positions.

It is apparent that the hours for closing or opening the switch may be changed as often as desired and at any predetermined closing and opening periods, and that the opening and closing operations will take place at the hours indicated on the setting dials with substantial accuracy, as the frictional mounting on the cam and gear members on the shaft 19 is sufficient to drive the parts with sufficient positiveness to obviate lost movement, while having sufficient freedom on the shafts to enable them to be set through the gearing connecting them with the setting dials.

Having thus described my invention, what I claim as new therein, and desire to secure by Letters-Patent, is:

1. The combination with a time-controlled arbor, of a shaft operable from the arbor, gear wheels frictionally mounted on and adapted for travel with the shaft, cams on said gear wheels, independent means engag-

ing the gear wheels to set the cams, a switch shaft, a stop member on the switch shaft, latches operable from the cams for controlling the stop member, and a switch operable 5 from said switch shaft.

2. The combination with a time-controlled arbor, of a shaft operable from the arbor, a gear wheel frictionally mounted on and adapted for travel with the shaft, a cam 10 connected with the gear wheel, a rotatable shaft, a sleeve frictionally mounted on the rotatable shaft and provided with a setting member, a pinion fixed to the sleeve and engaging the cam gear wheel, gear connection 15 between the cam shaft and the sleeve shaft, and a pointer on the sleeve shaft, for the purpose set forth.

3. The combination with a time-controlled arbor, of a cam shaft operable from the 20 arbor, combined cam and gear wheels frictionally mounted on the shaft and adapted for travel therewith, means for setting the combined cam and gear wheels, a switch shaft, a disk on the switch shaft having a 25 plurality of stops, independent latch members operable from the separate cams for controlling said disk, and a switch operable by the switch shaft.

4. The combination with a time-controlled 30 arbor, of a cam shaft operable from the arbor, a combined cam and gear wheel frictionally mounted on and adapted for travel with said shaft, a rotatable shaft, a pointer fixed on said rotatable shaft, a sleeve frictionally mounted on the rotatable shaft and adapted for travel therewith, a disk on said 35 sleeve for coöperation with the pointer to indicate a set hour, a pinion fixed on said sleeve and meshing with the cam gear, a pinion fixed on said rotatable shaft, a gear 40 wheel fixed on the cam shaft and meshing with the last named pinion, a switch shaft, a stop member on the switch shaft, a latch operable from the cam and adapted for engaging 45 the stop member, to control rotation of the switch shaft, a motor operably connected with the switch shaft, and a switch operable by the switch shaft.

5. The combination with a time-controlled 50 arbor, of a cam shaft operable from the arbor, independent gear wheels frictionally mounted on the cam shaft, cams fixed on said gears, independent, rotatable shafts, a driving gear wheel fixed on the cam shaft, said 55 independent rotatable shafts having pinions meshing with said driving gear wheel,

sleeves on said rotatable shafts, each having a dial, a pointer on each of said rotatable shafts adapted for coöperation with the dial to indicate a set hour, pinions fixed on the 60 sleeve and meshing with the separate cam gear wheels, a switch shaft, a disk on the switch shaft having protuberances on its opposite faces, separate latches operable by the separate cams for controlling travel of 65 the disk with its shaft, a motor for actuating the switch shaft, and a switch operable from said switch shaft.

6. The combination with a shaft, of a switch operable from the shaft, means for 70 actuating the shaft, a member on the shaft provided with circumferentially spaced pins, independently operable escapement members adapted for engagement with separate pins on said member, clock mechanism, a shaft 75 operable by the clock mechanism, gear wheels having frictional mounting on said shaft and each provided with a cam for actuating one of the escapement members, independent shafts, sleeves having frictional 80 mounting on the independent shafts, a gear wheel on the clock shaft, pinions on the independent shafts meshing with the gear wheel on the clock shaft, a gear wheel on each of said sleeves meshing with one of the cam 85 gear wheels on the clock shaft, a setting dial on each sleeve and a pointer on each independent shaft adapted for coöperation with a relative dial to indicate time of actuation 90 of a relative escapement member.

7. The combination with a switch, of a shaft, means for constantly retaining the shaft under revolving tension, crank connection between the shaft and switch, a disk on said shaft, pins projecting from opposite 95 faces of the disk, an escapement member pivotally mounted and adapted for holding engagement with one of said pins, a secondary escapement member pivotally mounted and having yoke arms, one provided with 100 a hook for engaging one of said pins and the other with a stop portion for engaging the other pin, clock mechanism, means operable by the clock mechanism for actuating the escapement members in proper sequence, and 105 means for setting said last named means.

In testimony whereof I affix my signature in presence of two witnesses.

ROY MURRAY.
